UNITED STATES PATENT OFFICE.

PIOTR SCUBELEK, OF WILMINGTON, DELAWARE.

SWORD AND GUARD ATTACHMENT FOR PISTOLS.

1,214,834.

Specification of Letters Patent.

Patented Feb. 6, 1917.

Application filed October 19, 1916. Serial No. 126,548.

To all whom it may concern:

Be it known that I, PIOTR SCUBELEK, a subject of the Emperor of Austria-Hungary, residing at Wilmington, in the county of New Castle and State of Delaware, have invented certain new and useful Improvements in Sword and Guard Attachments for Pistols, of which the following is a specification.

This invention relates to new and useful improvements in sword and guard attachments for pistols.

The primary object of the invention is the provision of a detachable sword member for automatic pistols provided with means performing the dual function of a band guard and magazine retainer for the pistol.

A further object of the device is the arrangement of a blade detachably arranged upon a pistol whereby the stock of the pistol forms a grip portion of the hilt of the sword, a swinging hand guard being arranged for retaining the cartridge magazine within the pistol stock.

A still further object of the invention is the provision of a ready attachment for a pistol in the form of a blade whereby the pistol may be employed either as a sword or for shooting in the ordinary manner, the blade being arranged forwardly of the pistol barrel and a shiftable retaining hand guard being arranged for normally connecting the stock of the pistol with the blade mounting member.

In the drawing forming a part of this application and in which like designating characters refer to corresponding parts throughout the several views:—

Figure 1 is a side elevation of the device partially broken away.

Fig. 2 is a sectional view taken upon line II—II of Fig. 1.

Fig. 3 is an enlarged detail sectional view taken upon line III—III of Fig. 1.

Fig. 4 is a perspective view of the positioning plate detached, and

Fig. 5 is a perspective view of the spring provided therewith.

The invention comprising an attachment for pistols, the same is herein illustrated in connection with a pistol 10 of substantially the usual automatic form having a barrel 11 and stock 12, the cartridge magazine 13 being removably arranged slidably within the said stock and having a cover plate 14 at the butt of the latter.

A bracket 15 is provided having a strap

portion 16 adapted for surrounding the barrel 11 removably secured thereto by means of a screw 17 while a sword or blade 18 is carried by the said bracket projecting forwardly of the muzzle 19 of the barrel positioned slightly therebetween.

A curved hand guard 20 is hinged as at 21 to the base 22 of the bracket 15 having a foot 23 normally arranged in flat engagement with the plate 14 adapted for retaining the magazine within the pistol stock. The said guard 20 is capable of lateral swinging movements as illustrated in dotted lines in Fig. 2 of the drawing whereby the foot 23 is released from the magazine 13 when it is desired to withdraw the latter from the stock 12.

An upturned free end 24 of the guard 20 normally overlies the rear face of the stock 12 and is provided with a normally outwardly projected releasing pin 25. A retaining plate 26 is transversely arranged within a recess 27 in the rear face of the stock 12, said plate having curved sided ribs 28 spaced from its opposite ends adapted for the seating reception therebetween of the enlarged end 29 of the said guard.

A substantially U shaped leaf spring 30 is secured within the recess 27 inwardly and in contact with the plate 26 whereby the said plate is normally projected with its outer ends 31 engaging the inner faces of the stop members 32 overlying the opposite edges of the said recess. The plate 26 is connected to the spring 30 by means of rivets 34 passing through slots 35 in the opposite end portions of the said spring. A helical spring 33 is provided for the pin 25 maintaining the inner end of the pin in contact with the plate 26 when the guard end 29 is seated upon the plate between the ribs 28 thereof.

The device being illustrated in its normal operative position in Fig. 1, it will be seen that the pistol stock 12 may be grasped by the hand for shooting the pistol and in which position the blade 18 may be readily employed as a sword, the guard 20 protecting the hand and forming with the said stock 12 a hilt for the sword. The guard 20 also normally positions its foot 23 in restraining engagement with the cartridge magazine 13 and is readily releasable by forcing the pin 25 inwardly depressing the plate 26 against the action of the spring 30 thereby allowing a lateral movement of the head 29 releasing the same from the ribs 28,

2

it being understood that the inner curved end of the pin 25 will ride over the inner curved face of the adjacent rib 28 during such lateral movement. When returning the 5 guard end 29 to its engaging position, the same as well as the inner end of the pin 25 will ride over the curved outer face of the adjacent rib 28 thereby depressing the plate 26 allowing the end 29 to seat upon the plate 10 between the ribs 28 thereof. When the foot 23 is positioned as shown in Fig. 1, the magazine 13 is retained within the grip 12 but is readily removable when the said guard 15 20 is swung laterally to its releasing position in either direction.

What I claim as new is:—

1. An attachment for automatic pistols comprising a bracket removably secured to the barrel thereof, a blade carried by the 20 said bracket projecting forwardly of the barrel, a hand guard hinged to the said bracket having a foot portion restrainingly positioned adjacent the butt of the pistol when the device is operatively arranged and 25 resilient retaining connections between the stock of the pistol and the extreme end portion of the said guard.

2. An attachment for automatic pistols having a cartridge magazine removable from 30 the butt end of the stock of the pistol, a bracket mounted adjacent the muzzle of the barrel of the pistol, a blade carried by the said bracket, a combined hand guard and magazine retainer hinged at one end to the 35 said bracket with an enlarged foot portion adjacent its other end normally arranged in contact with the said magazine within the operative path of movement thereof, and spring catch connections between the enlarged extreme end of the said guard and the 40 stock of the pistol.

3. An attachment for automatic pistols having a cartridge magazine removable from the butt end of the stock of the pistol, a bracket mounted adjacent the muzzle of 45 the barrel of the pistol, a blade carried by the said bracket, a combined hand guard and magazine retainer hinged at one end to the said bracket with an enlarged foot portion adjacent its other end normally arranged 50 in contact with the said magazine within the operative path of movement thereof, the stock of the pistol having a recess therein, a curved leaf spring secured within the said recess, a plate carried by the said spring normally projected substantially 55 flush with the adjacent surface of the stock and having curved sided spaced transverse ribs adapted for the seating reception of the said guard end therebetween and a spring pressed depressing pin for the said plate carried by the said guard end.

4. A device of the class described comprising in combination with a pistol, a bracket attached thereto, a combined hand 65 guard and magazine retainer pivoted at one end to the said bracket extending forwardly of the stock and spanning the butt of the latter when normally arranged, the said guard having an enlarged free end, the stock 70 of the pistol having a recess therein, a curved leaf spring secured within the said recess, a plate carried by the said spring normally projected substantially flush with the adjacent surface of the stock and having 75 curved sided spaced transverse ribs adapted for the seating reception of the said guard end therebetween and a spring pressed depressing pin for the said plate carried by the said guard end.

In testimony whereof I affix my signature.
PIOTR SCUBELEK.
